Des. 206,470
Patented Dec. 13, 1966

206,470

SWEATER HANGER

Daniel E. Gelles, Kerhonkson, N.Y. 12446
(1140 Broadway, New York, N.Y. 10001)

Filed June 16, 1966, Ser. No. 2,701

Term of patent 14 years

(Cl. D80—8)

FIG. 1

FIG. 2

FIG. 3

FIG. 5

FIG. 6

FIG. 4

FIGURE 1 is a front elevational view of a sweater hanger showing my new design;

FIGURE 2 is a bottom plan view thereof;

FIGURE 3 is top plan view thereof;

FIGURE 4 is an elevational view taken from one end thereof;

FIGURE 5 is a cross-sectional view taken on line 5—5 of FIGURE 1; and

FIGURE 6 is a cross-sectional view taken on line 6—6 of FIGURE 1.

I claim:

The ornamental design for a sweater hanger, substantially as shown.
